ADAPTER FOR FLASHLIGHT AND REVOLVER

Filed Dec. 9, 1940

2 Sheets-Sheet 2

Fig. 5.

Fig. 6: A cross-sectional view of a device showing internal components labeled 32, 34, 35, 36, 37, 38, 39, 40, 41, 42, 43, 44, and 45.

Fig. 7.

The image contains two technical line drawings of a device assembly, labeled Fig. 8 and Fig. 9.

Fig. 8: This drawing shows a top-down view of a circular component. The top surface features a central circular area with a textured or ribbed pattern. Surrounding this central area are several labeled parts: 59, 53, 60, 58, 34, 62, 61, 55, 3, 50, 56, and 55. The bottom of the circular component is supported by a base structure with labels 51, 63, and 52.

Fig. 9: This drawing shows a side view of the device. It consists of a large, elongated, oval-shaped housing. The top surface of this housing has a central circular area with a textured or ribbed pattern. Several labeled parts are visible on the top surface: 58, 59, 59, 60, 58, 61, 56, 61, and 5. The bottom of the housing is supported by a base structure with labels 51 and 63.

UNITED STATES PATENT OFFICE

2,314,061

ADAPTER FOR FLASHLIGHT AND REVOLVER

George W. Whaley, Van Nuys, Calif.

Application December 9, 1940, Serial No. 369,294

3 Claims. (Cl. 240—6.41)

This invention relates to an adapter for flashlight and revolver and in general relates to an improvement over the sighting device described and claimed in my United States Patent 2,132,063, patented October 4, 1938 for "Flash-lamp."

On page 1, lines 35 to 53 of the above patent, the statement is made that the flashlight must not be longer than the barrel of the gun as otherwise the muzzle blast would impinge on and damage the flashlight and dislodge the flashlight from proper seating relation upon the gun. As a consequence, the construction illustrated in the above patent, involves the use of a special type of flashlight. I now find that if the flashlight is longer than the barrel, the above noted damage is not serious and is more than offset by the convenience of being able to use a conventional flashlight. Consequently I have simplified and improved the patented construction, and have provided an adapter for removably holding a conventional type of flashlight as a unit which may or may not project beyond the muzzle. The accuracies of alignment of the gun with the flashlight as described in my former patent are substantially retained in the present simplified and improved construction. The present invention is illustrated by several embodiments, some of which are made of sheet metal which may be flexible enough so that it can be bent to permit slight adjustment of alignment of the gun with the flashlight.

An object of the invention, therefore, is to provide an adapter which will accommodate a conventional flashlight and which will serve as a rest to accurately align the gun with the flashlight.

For further details of the invention reference may be made to the drawings wherein:

Fig. 1 is a view in side elevation of one form 40 of the invention.

Fig. 2 is a vertical sectional view of the adapter of Fig. 1, the section being taken on line 2—2 of Fig. 3.

Fig. 3 is a view in end elevation of the adapter 45 of Fig. 1, looking in the direction that the gun is pointed.

Fig. 4 is a vertical sectional view on line 4—4 of Fig. 2.

Fig. 5 is a view in side elevation of a modified 50 form of adapter.

Figs. 6 and 7 are enlarged perspective views of the clamping bands which form the adapter of Fig. 5.

Fig. 8 is a front view in elevation of another 55

modified form of adapter which serves as a rest for the frame of the firearm, and with which the clamp of Fig. 7 may be associated. In other words, Fig. 8 is a modification of the clamp of Fig. 6.

Fig. 9 is a perspective view of the adapter shown in Fig. 8.

Referring in detail to the drawings, the adapter shown in Figs. 1 to 4 comprises an 10 adapter 1 having a socket 2 to receive the end of a conventional flashlight 3. The adapter 1 is provided with a band 4 which encircles an intermediate portion of the casing 63 of the flashlight 3. Band 4 may be secured to the 15 adapter 1 by screws such as 5. The adapter 1 may be cast of a single piece of material such as metal and it has an L shaped recess 6 lying between the spaced parallel L shaped flanges 9 and 10. Recess 6 as shown in Fig. 2, embraces 20 the lower half of the barrel 7 and the sides and front of the frame 8 of the firearm. Flange 9 may be higher than flange 10 as shown in Fig. 3 to guide the barrel 7 laterally into the recess 6. The adapter 1 has a wall 11 as shown in Fig. 2 25 which forms the bottom of the socket 2. On one side of this wall 11 is a band 12 which supports and surrounds the end of the flashlight 3. The other side of wall 11 has an angular L shaped support on rest 13 against the vertical portion 14 of which the front of the frame 8 is adapted 30 to fit and rest, and against the top 15 of which the bottom of the frame 8 is adapted to fit and rest. The adapter 1, underneath the end of the barrel 7 is provided with a projection 16 having 35 a semi-circular recess 66 to support the end of the barrel 7.

The flashlight 3 may be held in the hand, with the firearm 17 removably resting on the adapter 1 as shown in Figs. 1 and 2. The flashlight 3 may be readily removed from the adapter 1 by removing one or both of the screws 5 to remove the clamping band 4.

Instead of casting the adapter 1 of a single piece of metal or other material, with a band 4 therefor, I may make the adapter in the form of two sheet metal clamping bands 20 and 21 as shown in Fig. 5. Here again the adapter 20 and 21 accommodates a conventional flashlight 3 which may be held in one hand, while the revolver 17 is held by the other hand. Band 20 as shown in Fig. 7 comprises two similar pieces of sheet metal each having an intermediate semi-circular portion 22—26 which surrounds and fits the casing of the flashlight 3. The band portion 22 terminates at its lower end in an

apertured lug 23 through which a clamping bolt 24 is adapted to pass, this bolt also passing through a similar apertured lug 25 on the companion band portion 26. The band portions 22 and 26 at their upper ends have radially extending flat lug portions 27 and 28 respectively, apertured to receive a clamping bolt 29. The lugs 27 and 28 terminate in concave portions 30 and 31 to form a substantially semi-circular rest for the end of the barrel 7.

The band 21 may if desired as shown in Fig. 6, be formed of a single piece of sheet metal, having terminal lugs 32 and 33 adapted to be secured by the clamping bolt 34 and having intermediate semi-circular portions 35 and 36 adapted to encircle and clamp the end of flashlight 3. The portions 35 and 36 have spaced parallel upwardly extending portions 37 and 38 which are spaced apart to form a recess 39 to receive the front of the frame 8 and the adjoining portion of the barrel 7 as shown in Fig. 5. The lugs 37 and 38 are apertured to receive a clamping bolt 40 which with the bolt 34 may be employed to clamp the adapter 21 around the end of the flashlight 3 as shown in Fig. 5. The lugs 37 and 38 for a portion of the width thereof, have an integral elongated portion which is bent back to form an integral U shaped portion 41, with the one leg 42 of the U 41 lying close against the inside of lug 37, and with the other leg 43 of the U 41 lying close against inside of lug 38, and with the bight 44 of the U forming a flat shelf on which the bottom of the frame 8 is adapted to rest. The leg 42 has bent at right angles thereto a lug 45, the back of which serves as a stop for the end of flashlight 3, and the front of which serves as a rest for the front of frame 8.

In the form shown in Fig. 8, the adapter 50 which is clamped to the end of flashlight 3, and with which the front clamp of Fig. 7 may be associated, may be formed by drawing or stamping a single flat sheet of metal. If desired, this drawing or stamping may be accomplished in one operation, a T shaped slot may be cut in the bottom and back of adapter 50 so that the lugs 51 and 52 may be turned out in a second operation, and if desired the nut and bolt head recesses 53 and 54 may be stamped or formed in a third operation, although this third operation may be omitted if desired. As shown in Figs. 8 and 9, adapter 50 comprises a U shaped side wall 55 which forms a socket to house the end of flashlight 3 which can be inserted into the adapter 50 until the end of the flashlight strikes the other side of the vertical wall 56, the front of which fits and forms a rest for the front of the frame 8. The adapter 50 is provided with a recess 57 resulting in walls 58 and 59 which are spaced apart to embrace the front of frame 8 and the adjacent portion of barrel 7, like the lugs 37 and 38 in Fig. 6. The bottom of recess 57 is somewhat Z shaped, the upper branch 60 of the Z forming a horizontal portion which may not serve as a rest for the firearm as it is not needed for this purpose. The middle branch of the Z comprises the wall 56 before mentioned, and the bottom branch 61 of the Z comprises an extended flat portion like the shelf 44 in Fig. 6 to fit and support the bottom of the frame 8. The opposite sides of the wall 55 are apertured to receive a clamping bolt 62 which passes underneath the shelf 60 as shown in Fig. 8. The bolt 62, with the bolt 63 which passes through lugs 51 and 52 may be employed to clamp the end of a conventional flashlight 3 in the socket provided by the adapter 50.

In the forms shown in Figs. 5 and 9, the various adapters may be made of sheet metal which is light enough so that it may be bent slightly from the shape shown in order to accommodate 5 the flashlight and support it with its axis parallel to the barrel 7.

It will be understood that the band 12 in Fig. 2, like the band 35, 36 in Fig. 6, and the band formed by the wall 55 in Fig. 8, in effect each constitute a 10 ledge which is adapted to underlie and support the end of the flashlight 3. Also, the casing 63 of the flashlight 3 is here shown as cylindrical but it may have other shapes, but in any event it contains all of the usual batteries for the flashlight 3. If more than one battery is employed as is usual, all of these batteries would be in alignment, as distinguished from having two of them offset laterally and arranged at right angles to the axis of the light beam as shown in Fig. 5 of 15 my former patent, and as distinguished from the use of an L shaped flashlight casing as shown in Fig. 8 of that patent.

Various changes may be made in the invention without departing from the spirit of the following 20 claims. For example the various clamping bands shown may be slightly larger than the flashlight so that conventional shims not shown may be employed to adjust the axis of the flashlight into parallel relationship with the barrel 7 when 25 it is in position on the adapter.

I claim:

1. A firearm adapter comprising a socket 30 adapted to receive the end of a flashlight, said socket having a band adapted to surround the end of a flashlight casing, the exterior of said 35 socket having integral therewith spaced side walls with a shelf at the end of said socket providing an open groove to removably receive and support the lower front corner of the frame of a 40 firearm with the bottom of said corner resting on said shelf opposite the end of the flashlight, means for attachment to another portion of the 45 flashlight, and means providing an open rest for the end of the barrel of the firearm associated with said last mentioned means, said open groove being so located on said socket and said open rest being so located on said attachment means that when said socket and attachment means are in 50 position on a flashlight, said rest and said groove are in position to support the firearm with the axis of the barrel of the firearm substantially parallel to the axis of said flashlight and above the flashlight when the latter is horizontal, said open groove and said open rest being free from 55 attachment to the firearm and opening outwardly in the plane of the axes of the firearm barrel and the flashlight to permit the firearm to readily separate from said adapter on recoil.

2. A firearm adapter comprising a socket having 60 a band to encircle the end of a conventional flashlight casing, said band having integral therewith and on the exterior thereof a pair of spaced walls extending part way across the end of said band and lengthwise thereof and forming an open 65 groove to receive the sides and front of the frame of a firearm, a shelf between said walls at the end of said band, means for attachment to an intermediate portion of the flashlight, said attachment means comprising an open rest for 70 the end of the barrel of the firearm, said open groove being so located on said band and said open rest being so located on said attachment means that when said band and attachment means are in position on a flashlight, said rest and said groove are in position to support the 75

6.41

2,314,061

3

- firearm with the axis of the barrel of the firearm substantially parallel to the axis of said flashlight and above the flashlight when the latter is horizontal, said open groove and said open rest being free from attachment to the firearm and opening outwardly in the plane of the axes of the firearm barrel and the flashlight to permit the firearm to readily separate from said adapter on recoil.
3. Means for supporting a firearm barrel above

5

10

and substantially parallel to the axis of a flashlight, said means comprising a socket to receive the end of the flashlight, said socket having an external shelf opposite the bottom of said socket, said shelf extending substantially parallel to the axis of said socket and forming a support for the bottom of the frame of the firearm, and external spaced walls on said socket and associated with said shelf for embracing the sides of said frame.

GEORGE W. WHALEY.
